UNITED STATES PATENT OFFICE.

MALCOLM MACLEOD, OF TORONTO, ONTARIO, CANADA.

HEATING OF LOCK AND DOCK GATES, MARINE VESSELS, AND THE LIKE.

1,104,914.

Specification of Letters Patent. Patented July 28, 1914.

Application filed November 1, 1913. Serial No. 798,769.

To all whom it may concern:

Be it known that I, MALCOLM MACLEOD, a subject of the King of Great Britain, and resident of Toronto, in the Province of Ontario, Dominion of Canada, have invented certain new and useful Improvements in the Heating of Lock and Dock Gates, Marine Vessels, and the like, of which the following is the specification.

10 My invention relates to the heating of lock and dock gates, marine vessels and the like, and the objects of my invention are to prevent the formation of ice thereon and to obviate the other objections due to such 15 formation, and it consists essentially of providing a heated zone on such vessels, dock and lock gates located partly above and partly below the water line, the parts being arranged and constructed in detail as hereinafter more particularly described by the 20 following specification.

Figure 1 is a view partly sectional of the hull of a ship showing my device thereon. Fig. 2 is a perspective view of a lock gate 25 showing my device attached thereto. Fig. 3 is a view of my device as it may be attached to a dock gate presently in use. Fig. 4 is a cross section of the lower part of the gate.

30 Like letters of reference refer to like parts in the several drawings.

Referring to the drawings, A represents part of a ship of any type consisting of an inner and an outer hull. 1 represents the 35 space located between such inner and outer hull adapted to form a chamber through which hot gases are designed to be passed. The ribs of the vessel extend into such chamber 1 and are designed to act as baffle 40 plates to the gases passing therethrough.

Any source of heat may be employed and the gases after leaving the hull are returned to be reheated at the source of supply.

Referring to Figs. 2, 3 and 4, B represents 45 a lock gate hinged in the usual manner to the supporting wall C. D represents a casing attached thereto and extending along the lower part of the gate, such casing consisting of an outer shell 2 designed to form 50 a space 9 between the face 3 of the gate B and the inner face 4 of the shell 2, the edges of the said casing being flanged as shown at 8, and adapted to be secured to the said gate by means of the rivets 7. The space 9 55 is subdivided by vertical baffle plates 10 fixed to the top and bottom sides and ex-

tending nearly to the opposing face. 11 represents the inlet from the source of supply of the hot gas which passing between the baffle plates 10 is discharged through the 60 pipe 12 to be reheated at the source of supply. 13 represents a casing extending in and along the supporting wall C. 14 represents a pipe through which hot gases are supplied to the casing 13, the comparatively 65 cold gases being carried back to the source of supply by means of a pipe not shown. The casings D and 13 are also adapted to be secured to a lock gate already in use, but the method of fixing the casings varies in 70 each case with the existing conditions. The method utilized of securing the casing 2 to the gate, as shown in Fig. 3, is the same as that shown in Fig. 2 and shown in detail in Fig. 4. The casing 13 will whenever 75 possible be built into the wall as shown in Fig. 2, or supported in any other suitable manner which will depend entirely on the structure of the lock gate. In Fig. 3 a piece of timber is located above the casings 2 and 80 13 and attached thereto by the pipes 11 and 12 and the pipe 14 and by any other suitable manner, such as bolts etc. should it be found necessary, such timber being designed to protect the casings from impact with vessels 85 or any other floating object.

Although my device is here shown adapted to hot gases it can also be arranged to suit electrical and other means of heating and is adapted to be fixed to vessels, water 90 gates of all classes, dry docks, flumes, wharves and the like.

It will be seen by the use of this device that dock gates and the like which are capable of being rendered useless during 95 cold weather are always kept in a fit condition to be easily and effectively used.

As many changes could be made in the above construction and many apparently 100 widely different embodiments of my invention, constructed without departing from the spirit or scope thereof, it is intended that all matter contained in the accompanying specification and claims shall be interpreted as illustrative and not in a limiting sense.

What I claim as my invention is:

1. The combination with lock gates of a 110 casing fixed to and extending along the lower part of such gates and designed to form an annular space between the face of such gate and the inner face of the said

casing, and means of supplying heat thereto, as and for the purpose specified.

2. The combination with a lock gate of a casing extending on and along the bottom part of such gate, a casing located in the supporting walls of such gate and means of supplying heat thereto, as and for the purpose specified.

3. The combination with lock gates of a casing extending on and along the bottom part of such gate, a casing located in the walls means of protecting such casings and means of supplying heat to such casings, as and for the purpose specified.

15. 4. The combination with lock gates of a casing extending along the bottom part thereof, a casing located in the supporting wall of such lock gate, a rectangular strip of resilient material extending along and 20 above the top of such casings, and means of supplying heat to such casings, as and for the purpose specified.

5. The combination with lock gates of a

casing extending on and along the bottom part thereof, baffle plates located in said 25 casing, a casing attached to the supporting wall of such gate, baffle plates located in said casing and means of supplying heat to such casings, as and for the purpose specified.

6. The combination with a lock gate, of a casing extending on and along the bottom part thereof, baffle plates located in said 30 casing, a casing attached to the supporting wall of such gate, baffle plates located in said casing, inlet pipes connected to such 35 casings through which hot gases are designed to be passed and discharge pipes connected to said casings, as and for the purpose specified.

In witness whereof I have hereunto set 40 my hand in the presence of two witnesses.

MALCOLM MACLEOD.
